Philadelphia, Pa., a corporation of Pennsylvania

Application April 29, 1944, Serial No. 533,354

9 Claims. (Cl. 62—115)

1

This invention relates to refrigerating apparatus and particularly to an improved refrigerant circulating system. More specifically the invention has reference to an improved multi-stage motor-compressor unit particularly adapted for use in refrigerators of a type affording the low-temperature conditions required for frozen foods. Neither the single nor multi-stage motor-compressor units heretofore known in the refrigerator art are well adapted for either practical or efficient operation in the newer types of refrigerator in which at least one compartment is maintained at temperatures ranging, for example, from 0° to -20°, necessitating a compressor having a wide capacity range. Because of the relatively large volume of refrigerant which must be handled by the compressor at such low operating temperatures, a single-stage unit having an adequate capacity range would necessarily be more bulky than the ordinary single-stage unit now in common use in standard types of refrigerators and would therefore be undesirable for use in a "home" refrigerator wherein conservation of space is an important factor. Also, a single-stage unit of this size would require a motor having a relatively high H. P. rating to accommodate the extreme peak load experienced at the high initial pressures, and the motor would then operate at low efficiency at the reduced normal running pressure when the motor load would correspond to only a fraction of its capacity.

The introduction into the art of multi- or two-stage compressors has afforded an increased B. t. u. capacity range in a unit comparable in size to that previously used in "home" refrigerators having the conventional freezing and food storage compartments. However, use of this type of unit results either in detrimental motor overload at the aforesaid high initial pressures or entails the use of a more powerful motor with attendant lower efficiency of operation at the reduced normal running pressures.

An important object of the present invention is to provide an improved multi-stage motor-compressor unit more adequately filling the requirements of the advanced types of domestic refrigerator.

Another important object of the invention is the provision of such a motor compressor characterized by practical and efficient operation over a relatively wide range of suction pressures.

It is also an important object to provide in a refrigerant circulating system a motor-compressor unit for low temperature evaporator opera-

tion, having a substantially constant B. t. u. capacity over a wide range of suction pressures so as to present a substantially constant motor load regardless of suction pressure fluctuation.

5 A further object of the invention is to provide a motor-compressor unit automatically responsive to a pre-selected suction pressure value for operation selectively as a single or multi-stage unit.

10 A more specific object of the invention is to provide a multi-stage motor-compressor unit of a size suitable for domestic refrigerator use, said unit including a motor of relatively low H. P. and having a wide suction pressure capacity range throughout which said motor is operative at substantially peak efficiency.

15 A still more specific object of the invention is to provide a two-stage motor-compressor unit in which a substantially constant pressure is delivered from the low-pressure pump to the high-pressure pump over at least a portion of the suction pressure capacity range of the unit.

20 A still further object of the invention is to provide a motor-compressor unit adapted to operate as a single-stage unit at high suction pressures and as a two-stage unit at lower suction pressures.

25 Another object of the invention is to provide a motor-compressor unit having means responsive to suction pressure for automatically increasing the B. t. u. capacity of said unit.

In the attached drawings:

30 Figure 1 is a diagrammatic illustration of a refrigerator system embodying the invention;

35 Figure 2 is a fragmentary vertical sectional view of a hermetically sealed motor-compressor unit embodying the invention;

Figure 3 is a fragmentary sectional view on the line 3—3 of Figure 2;

40 Figure 4 is a fragmentary sectional view on the line 4—4 of Figure 2;

Figure 5 is a fragmentary-sectional view on a considerably enlarged scale taken on the line 5—5 of Figure 4;

45 Figure 6 is a graph illustrating an operating cycle of a preferred embodiment of the invention;

Figure 7 is a fragmentary diagrammatic view of a modified form of the invention; and

50 Figure 8 is a graph illustrating an operating cycle of a modified embodiment of the invention.

Referring to the drawings, and more particularly to Figure 1, the refrigerant circulating system 10 therein illustrated includes a conventional condenser 11 from which liquid refrigerant flows

through a capillary tube 12 into an evaporator 13 of either the series or parallel feed type, as desired. Gaseous refrigerant passes from the evaporator 13 through a suction line 14 into the compressor 15 where it is compressed and from which it passes through a tube 16 into the condenser 11, thereby completing the cycle. The capillary tube 12 and suction tube 14 may be in heat exchange relation as illustrated.

The compressor 15, as more clearly illustrated in Figure 2, is of the multi-stage (in this instance two-stage) hermetically sealed type and includes a shell or housing 20 comprising a pair of opposed bowl or dome-shaped members 21 and 22 sealed together about their abutting peripheral flanges 23 and 24 as by welding, indicated at 25. Legs 26 (Figure 1) are provided for mounting the shell within the machine compartment of a refrigerator (not shown).

Mounted within shell 20 upon a plurality of resilient supports, of which one is indicated at 27, is a main frame member 28 provided with a central vertical bore forming a bearing 30 for a shaft 31. Frame 28 is also provided with up-standing wall portions 32 for supporting the stator 33 of an electric motor 34. The rotor of motor 34, located within the stator and generally designated by the numeral 36 (Figure 1), is rigidly secured to the upper end of shaft 31.

Shaft 31 has an integral lower extension or eccentric 37 having its vertical axis offset horizontally relative to the normal axis of shaft 31. This eccentric is adapted to cooperate with a "scotch yoke" 38 in reciprocating a pair of horizontally opposed integral pistons 39 and 40 in high and low pressure cylinders 41 and 42 in the lower portion of frame member 28, said piston-cylinder assemblies constituting respectively elements of high and low pressure pumps 43 and 44. The yoke assembly comprises a bearing element 45 which moves with the eccentric 37 and slides transversely in the yoke member 46 of which member the pistons are a part.

The cylinder of the low pressure pump 44 comprises a cylinder head 47 which is secured to frame 28 as by machine screws 49 (Figure 4). Cylinder head 47 is provided with inlet apertures 50 normally closed by a spring leaf valve 51 fastened to the inner surface of head 47, as by screws 52, and comprising a pair of legs 53, 53 depending from a transverse portion 54 through which portion pass the screws 52. To prevent oil from entering these apertures from the crankcase 22a formed by the lower portion 22 of shell 20, an oil-tight hood 55 is secured thereover as by screws 55a. From the hood 55 an open ended tube 56 extends upwardly to a point sufficiently distant from the oil level 57 to prevent oil from entering the open end to find its way into pump 44. If desired a baffle 58 may be fitted around the tube to prevent oil from splashing or foaming into its open end.

Still with reference to Figure 2 it may be seen that the cylinder of the high-pressure pump 43 comprises a valve plate 60 and cylinder head 61 secured to frame 28 as by machine screws 62. Valve plate 60 fits snugly in a recess 63 in the head 61, and gaskets 64 on both sides of the outer edges of the plate seal the cylinder against leakage of refrigerant. Valve plate 60 is provided with outlet apertures 65, and these apertures are normally closed by a resilient disc valve 66 snugly fitting into a recess 67 in cylinder head 61 and resiliently held in such position by a coil spring 68 seated in a recess 69 also in the head

61. A channel 70 through the integral pistons 39 and 40 provides communication from cylinder 42 to cylinder 41, said channel at the end adjoining the cylinder 41 terminating in a circular groove 71 which is normally closed by a resilient disc valve 72 secured to the piston as by a screw 74.

A plurality of recesses 75 (Figure 3) are provided in the walls of the recess 67 in head 61 to permit passage of gases from beneath disc valve 66 into said recess. Open communication between recess 67 and discharge tube 16 is afforded by a tube 75a, muffler 76, and tube 77, one end of tube 75a being fitted into an outlet aperture 78 in head 61, and the other end being connected to the muffler 76 from which the tube 77 extends to and through the shell 20 by way of an air-tight leak-proof joint shown at 79. One end of the discharge tube 16 is secured to the outer end of tube 77, and the other end is attached to one end of the condenser tube 80 so as to afford open communication between the recess 67 in cylinder head 61 and the condenser 11. Tube 77 may be extended to loop around the frame 28 prior to its attachment to shell 20, thereby to reduce vibration at the point of attachment. Muffler 76 may be cast integrally with the frame 28 or cylinder head 61, if desired.

While any suitable lubricating system may be incorporated in the unit, an impeller type of oil pump has been shown and includes a casting 81 hollowed out, as at 82, to form a recess or cavity for reception of an impeller 83, said impeller being attached to the lower end 84 of an integral small diameter axial extension 85 of shaft 31, which extension passes through a central bearing 86 in the casting 81. A cover plate 87 encloses the recess and together with the casting 81 is fastened to the lower portion of the frame 28 as by screws 88. Open communication between crankcase 22a and recess 82 is provided by an aperture 89 in the cover plate 87. A passage 90 in the head has one end in communication with recess 82 at a point remote from aperture 89 and its other end in registry with an axial bore 91 in the shaft 31, which bore extends upwardly to a radial bore 92 having connection with a spiral channel 93 about the periphery of shaft 31. Another radial bore 94 in eccentric 37 provides a means for lubricating the "scotch yoke" 38.

When the motor 34 is rotating the impeller 83 sucks oil from crankcase 22a into recess 82 through aperture 89 and forces it by way of passage 90 upwardly through the axial bore 91 and through the radial bore 92 into channel 93 to lubricate the main shaft bearing 30. Oil also passes through radial bore 94 to lubricate the "scotch yoke" 38. From the top of spiral channel 93 oil flows into a peripheral channel (not shown) from which it overflows and finds its way downwardly over the frame and pumps, back into the crankcase to repeat the cycle.

The above described compressor mechanism is in accordance with well-known principles in the compressor art and the invention does not lie in such mechanism, per se, except in so far as associated with the following structure.

In accordance with the present invention and as clearly illustrated in Figure 5, there is provided in cylinder head 47 of low pressure pump 44 a pressure-responsive valve, generally indicated by reference numeral 100. This novel valve means, as will be fully brought out, is adapted to render one of said pumps ineffective

under certain conditions of operation. In the broader aspect, valve means 100 may take any one of several known forms. However, the valve preferably is of the bellows type and comprises a base member 101 secured in an aperture 102 in the head 47 as by a threaded extension 103. An intermediate peripheral nut-shaped flange or projection 104 is adapted to receive a wrench for effecting such attachment. A gasket 105 is interposed between the flange and cylinder head 47 to effect an air-tight seal at that juncture, and a flange 106 of the hood 55 also extends upwardly beneath the flange 104 to provide additional connection between the hood and the cylinder head. Extending in a direction opposed to that of threaded extension 103 is an extension 107 having threaded thereon a dome or cap 108 provided with apertures 109 and supporting the pressure-responsive element 110 of the valve. Base member 101 has an axial bore or aperture 111 providing communication with the interior of shell 20 through apertures 109. A valve seat 112 on the face 113 of projection 107 surrounds the mouth 114 of aperture 111 and is adapted to cooperate with plate 115 of element 110 to control communication between shell 20 and cylinder 42.

The valve plate 115 has an annular flange 116 to which is secured, as by welding or other suitable method, one end of a bellows 117, the other end of the bellows being similarly secured to a peripheral flange 118 of an inwardly projecting centrally disposed member 119 thereby forming within the bellows an air-tight cell 120 which may be sealed at atmospheric or other desired pressure. A coil spring 121 is disposed around member 119 within the cell 120 and normally holds the plate 115 and flange 118 in spaced relation. For supporting element 110 in a centrally disposed position relative to the dome 108, member 119 is provided with a central bore or recess 122 which receives one end 123 of a screw 124 threaded through an inwardly extending internally threaded boss 124a of dome 108. By turning the screw 124 inwardly or outwardly element 110 may be set at some predetermined pressure-responsive value which the external pressure on the bellows would have to exceed to move plate 115 from its seat 112 to establish communication between cylinder 42 and shell 20. A lock nut 125 is provided on the screw externally of dome 108 for fixing the valve in its selected pressure-responsive adjustment. The dome or cap prevents surging of large quantities of oil through aperture 111 when the valve is open.

The operation of the apparatus is as follows: Assume that the refrigerator in which the apparatus has been installed contains a compartment to be cooled to and to be maintained at, say -10° F. Assume also that the refrigerator has been installed in a room of approximately 80° F. The refrigerant used may be the well-known "Freon 12," and the pressure-responsive valve 100 is set to operate at 30 pounds gauge, external pressure. In other words, when the external pressure upon the pressure-responsive element 110 of the valve exceeds 30 pounds, bellows 117 will collapse and unseat valve plate 115 from its seat 112 and open communication of cylinder 42 with the interior of shell 20 through aperture 111. When the pressure upon element 110 is less than 30 pounds, plate 115 is urged against its seat by the element to close the aforesaid communication between the cylinder and shell 20.

As the system illustrated in Figure 1 is of the continuously open capillary type, the pressure,

under the above conditions, will be equalized throughout at, say, approximately 84 pounds and the pressure-responsive valve 100 will be open. When it is desired to initiate operation of the system the necessary electrical connections are made to start the motor which rotates shaft 31 and with it the eccentric 37 thereby actuating the "scotch yoke" and reciprocating pistons 39 and 40 in cylinders 41 and 42.

Cylinder 42 is in open communication with the shell interior by reason of open valve 100 so there is no pumping action by actuation of piston 40, and the operation of the unit is conventional single-stage, as indicated by line 126 of Figure 6. When piston 39 moves in a direction outwardly of its cylinder 41, disc valve 72 is moved from its seat on the piston by the pressure differential created, thereby causing gaseous refrigerant to flow from within the hermetically sealed shell 20, through open valve 100 into cylinder 42 from which it passes through channel 70 past disc valve 72 into cylinder 41 of high pressure pump 43 at its initial pressure of 84 pounds gauge. Upon the return stroke of the piston, disc valve 72 is moved to its closed position and the refrigerant is forced past disc valve 66 through aperture 75 into recess 67 from which it passes through aperture 78, tube 75a, muffler 76, and tubes 77 and 16 into condenser 11.

Continued operation of the unit as single-stage draws gaseous refrigerant from the evaporator through tube 14 and into shell 20 at decreasing suction pressures as the temperature of the evaporator is lowered. When the pressure within the shell decreases to 30 pounds gauge, pressure responsive element 110 closes aperture 11 and refrigerant then will enter cylinder 42 only through aperture 50, by way of tube 56 and hood 55, the valve 51 being unseated or opened on the suction stroke of piston 40 and closed on its compression stroke. It will be understood, of course, that the pressure value of 30 pounds gauge has been selected only by way of example, and that by pre-selection the valve 100 may be set at other desired pressure-responsive values by adjustment of screw 124.

As stated, valve 100 closes at 30 pounds pressure in shell 20, but at that value, immediately opens upon initiation of the compression stroke of pump 44 by reason of the increased pressure in cylinder 42, to thus vent the excess back into the shell 20. As the pressure within the shell drops below 30 pounds the valve 100 stays closed for longer periods, in other words, it stays closed until the pressure in cylinder 42 exceeds 30 pounds, at which value the valve opens to vent the excess back into the shell. This operation continues over a wide range of lowering pressures within shell 20 until pump 44 is no longer able to increase the pressure received within cylinder 42 above 30 pounds. Thus a substantially constant weight of refrigerant is fed from cylinder 42 into cylinder 41 over a wide range of suction pressures, as represented by the horizontal line 127 in Figure 6. When pump 44 is no longer able to raise above 30 pounds the pressure of the refrigerant received within its cylinder 42 from shell 20, the valve 100 remains closed and continued operation of the unit is then conventional two-stage, as represented by line 128 in Figure 6.

With regard to the above described operation of the unit it should be understood that upon the initial stroke of piston 39 there is no discharge pressure to overcome, excepting the weight of discharge valve 66, and it should be

pointed out that the latent-heat content of the warm refrigerant prior to operation of the apparatus is approximately 60.5 B. t. u. per pound at 80°, which means that a 1.5 cubic inch per stroke displacement pump with a 1750 R. P. M. motor, would displace approximately 1.5 cubic feet per minute by volume and (with "Freon 12" having a density of 2.35 pounds per cubic foot) that approximately 210 B. t. u. per minute would be the starting rate of discharge into the condenser, said condenser being designed to dissipate a condenser output of approximately 10 B. t. u. per minute at normal running pressures.

Because large condensers are uneconomical and unnecessary at normal operating pressures, it is customary to use small condensers in domestic size refrigerators, and such condensers are inadequate to dissipate the aforesaid large B. t. u. output of the compressor during the initial running period. Consequently the discharge pressure of pump 43, or that back pressure from the condenser which resists opening of the disc valve 66, increases rapidly from zero on the initial stroke of the pump to perhaps 350 pounds in as few as two minutes or even less, depending upon the R. P. M. rate of the motor. This pressure must be slightly exceeded by the pressure in cylinder 41 before gas will start passing exhaust valve 66 into the condenser. In addition to reaching this high side pressure, it must overcome the exhaust valve pressure or weight, with a consequent further increase in pressure. At such high pressures it is well-known that volumetric efficiency is low.

Volumetric efficiency of a pump is defined by the ratio between the volume actually pumped per revolution divided by the volume calculated from the bore and stroke. The volume actually pumped in refrigerator motor-compressor units is dependent upon the discharge pressure coupled with re-expansion of the small volume of gas still remaining in the cylinder between the piston and cylinder head at the completion of the compression stroke. This small volume is under high pressure and as the piston returns on the suction stroke this gas expands and partially fills the cylinder chamber to decrease by this amount the quantity of gas that may enter the cylinder from the low pressure or suction side of the system, from shell 20 in the present instance. There are also other incidental losses such as those due to leakage past the piston back into the shell and from super-heating of the gas resulting from its contact with the heated motor, etc., all tending to decrease the volumetric efficiency. Thus it may be seen that it is extremely advantageous for efficient and economical operation to keep discharge pressures and consequently compression ratio as low as possible.

With the above in mind it will be understood that effective operation of low pressure pump 44 in addition to operation of the high pressure pump during the initial operating period would discharge a much greater weight of gas into the condenser thereby increasing the discharge pressure more rapidly and to a much higher value, and would require a motor having a higher HP rating to overcome this increased load. Such a motor would be increasingly inefficient as the pressures lowered, and extremely so at the low pressure encountered at -10° F. In this respect it may be stated that a particular requirement of all motor-compressor units is that the motor must have a capacity sufficient to meet the relatively infrequent peak or maximum load. It should

be understood too that if the unit were allowed to continue operation as a single-stage unit it would do so in a manner similar to a conventional single-stage compressor unit, but as the size and pump displacement of the single cylinder is necessarily small in domestic size units, its B. t. u. capacity at low suction pressures would be inadequate for the desired extremely low temperatures, such as -10°, see line 126a, Figure 6.

Comparing the operation of the present unit with that of known single and two-stage motor-compressor units having a capacity substantially equal to a unit corresponding to the above described embodiment of the invention, it should be understood that each of the known types would require a motor having a high H. P. rating to accommodate the peak starting load, with a resultant greatly decreased operating efficiency at the reduced pressures incident to low temperature operation.

While it is impossible to alter the above condition in single-stage operation, the present invention provides a two-stage construction wherein the starting loads are decreased to an extent equal to the capacity of the low pressure pump, with a resultant comparative decrease in H. P. requirement, and increased operating efficiency at low temperature operation. Let it be assumed that the reduced H. P. motor of the present invention be somewhat overloaded (but within its limits) under the pressures encountered at the initiation of operation as a single-stage unit, by the time valve 100 closes and the second stage has functioned intermittently, as described, the motor will have operated at substantially peak efficiency over a wide range of pressures, and there will be little loss of efficiency after initiation of conventional two-stage operation and continued operation to the desired low temperature.

It is evident from the above that the invention has provided an improved "home" size multi-stage motor-compressor unit characterized by efficient operation over a wide range of suction pressures. It is evident also that a unit has been provided which is capable of automatically changing its operating cycle from single to two-stage, or vice versa, depending upon suction pressures. Further, during such change of cycle, it is capable of operating automatically at a B. t. u. capacity relatively constant over a wide range of suction pressures so as to present a constant motor load regardless of suction pressure fluctuation, and this while utilizing a minimum H. P. motor at substantially peak efficiency throughout the capacity range.

Figure 7 illustrates a modified form of the invention and includes in place of pressure-responsive valve 100, a solenoid actuated valve 130 mounted over aperture 102a in cylinder head 41a, and having a valve plate 115a adapted to seat on an annular seat 133 surrounding aperture 102a. A pressure-responsive switch 134 is adapted to open and close a suitable electrical circuit 135 for actuating valve 130 to and from its seat 133. Switch 134 may be set to operate at any pre-selected suction pressure value by turning screw 136. A lock nut 137 is provided to "fix" such setting of the switch.

In operation of this form of the invention, switch 134 closes at high suction pressures to complete the circuit 135, thus actuating the solenoid to draw valve plate 115a away from its seat 133 to open communication between cylinder 42 and casing 20. When the suction pressure has

dropped sufficiently, as explained more fully later, switch 134 operates to break circuit 135 to allow the valve plate to be moved, under pressure of spring 138, to its closed position on seat 133 to close the aforementioned communication of cylinder 42 with shell 20. The suction pressure valve is preferably set at a pressure value which, when the valve closes, will not increase the motor load of the two-stage operation to a value greater than the starting load of the initial single-stage operation. The advantages of two-stage capacity range are thus acquired without the initial motor overload characteristic usually attending such units.

While it is true that the present invention as illustrated is particularly adapted for use in "home" size two-stage hermetically sealed motor-compressor units, its application should not be considered to be so limited as its principle may extend to large multi-stage industrial units of similar type, large and small multi-stage units of the so-called "open type," and is also applicable to the rotary type of compressor.

I claim:

1. In a refrigerant circulating system including an evaporator and a condenser, a two-stage compressor unit including a sealed housing having communication with said evaporator for receiving gaseous refrigerant therefrom, a low-pressure pump and a high-pressure pump mounted within said housing, means for actuating said pumps, said low-pressure pump being adapted to receive gaseous refrigerant from within said housing to compress said refrigerant and to pass it into said high-pressure pump to be further compressed and discharged into said condenser wherein it is liquefied and subsequently returned to said evaporator, and means responsive to high pressures within said housing for rendering said low-pressure pump ineffective whereby said unit may operate as a single-stage unit.

2. In a refrigerant circulating system including an evaporator and a condenser, a two-stage motor-compressor unit including a sealed housing having communication with said evaporator for receiving gaseous refrigerant therefrom, a low-pressure pump and a high-pressure pump mounted within said housing, a motor for actuating said pumps, said low-pressure pump being adapted to receive gaseous refrigerant from within said housing to compress said refrigerant, and to pass it into said high-pressure pump to be further compressed and discharged into said condenser wherein it is liquefied and subsequently returned to said evaporator, and means responsive to pressures within the housing for rendering said low-pressure pump ineffective, whereby said unit may operate as a single-stage unit, said means being automatically responsive to reduced housing pressures for rendering said low-pressure pump effective, whereby said unit may operate at a relatively constant capacity over a wide range of suction pressures so as to present a relatively constant load upon the motor regardless of suction-pressure fluctuation.

3. In a refrigerant circulating system including an evaporator and a condenser, a two-stage motor-compressor unit including a sealed housing having communication with said evaporator for receiving gaseous refrigerant therefrom, a low-pressure pump and a high-pressure pump mounted within said housing, a motor for actuating said pumps, said low-pressure pump being adapted to receive refrigerant from within said housing, to compress said refrigerant, and to pass it into said high-pressure pump for further com-

pression and subsequent discharge into said condenser wherein it is liquefied and thereafter returned to said evaporator, and means responsive to pressure within the housing for rendering ineffective said low-pressure pump whereby during a portion of said unit operating cycle the unit may operate as a single-stage unit, said means being automatically responsive to reduced suction pressures for rendering said low-pressure pump operative whereby further operation of the unit is two-stage.

4. In a refrigerant circulating system a motor driven multi-stage compressor unit including a high-pressure pump, a low-pressure pump, and valve means for rendering the low-pressure pump ineffective during a portion of an operating period of said unit, said valve means comprising a port providing communication between the said low-pressure pump and the source of gaseous refrigerant, a valve element controlling said port and arranged so that internal pump pressure tends to open the valve, pressure-responsive means actuatable by pressure of said gaseous refrigerant to open the valve, and means for predeterminedly loading the valve against said opening pressures.

5. In a refrigerant circulating system a motor driven multi-stage compressor unit including a high-pressure pump, a low-pressure pump, a bypass port in the low-pressure pump operative when open to render the pump ineffective, and a valve controlling said port, said valve being responsive to pressure from within the pump to uncover the port, and means operatively connected to the valve for resisting with predetermined pressure the tendency of said internal pump pressure to uncover the port, and means responsive to the pressure prevailing at the suction side of the pump for uncovering the port independently of said internal pressure when said suction pressure exceeds said predetermined pressure.

6. A multi-stage compressor unit including a low and a high pressure pump, a by-pass port in the low pressure pump adapted when open to render the pump ineffective, a valve controlling the port and responsive to pressure from within the pump to uncover the port, and means operatively associated with the valve and exerting thereon a predetermined pressure resisting the tendency of said internal pump pressure to uncover the port, said means being responsive to pressures at the suction side of the pump to open the valve when said suction pressure exceeds said predetermined pressure.

55. 7. A multi-stage compressor unit including interconnected high and low pressure cylinders and pistons operating synchronously therein, a normal valve-controlled suction port in the low pressure cylinder, a by-pass port in the low pressure cylinder adapted when open to render the said cylinder inoperative, a valve controlling said by-pass port and responsive to pressure from within the said cylinder to uncover the port, means for loading the valve to a predetermined opening pressure, and means operatively connected to the valve and adapted for actuation by fluid pressure at the said suction port in excess of the said loading pressure for opening the by-pass valve independently of said internal cylinder pressure, 70 said valve opening means operating also to augment the pressure within the cylinder during compression stroke of the contained piston to open the valve against the loading pressure.

8. A multi-stage compressor unit including inter-connected high and low pressure cylinders and

11

pistons operating synchronously therein, a normal valve-controlled suction port in the low pressure cylinder, a by-pass port in the low pressure cylinder adapted when open to render the said cylinder inoperative, a valve controlling said by-pass port and responsive to pressure from within the said cylinder to uncover the port, means for loading the valve to a predetermined opening pressure, and means actuated by external pressure at the said suction port for opening the 10 valve against said loading pressure.

9. In a closed refrigerant circulating system, a multi-stage compressor unit including interconnected high and low pressure cylinders and pistons operating synchronously therein, an evaporator connected to the suction side of the low pressure cylinder, a condenser connected to the discharge side of the high pressure cylinder, and means for connecting the condenser with the evaporator to complete the refrigerant circuit, 15 a check valve in the connection between the evaporator and the low pressure cylinder, a by-pass for said check valve, a valve controlling said by-pass, said valve being responsive to the internal pressure of said low pressure cylinder to open the by-pass, means for loading the valve to

5 a predetermined opening pressure, and means operatively connected to the valve and adapted for actuation by the suction pressure to open the valve against said loading pressure when the suction pressure exceeds the latter.
